UNITED STATES PATENT OFFICE.

JOHN WILLIAM EDWARD BETTLES, OF BIRMINGHAM, ENGLAND.

MANUFACTURE OF FENCING, RAILINGS, OR GATES.

Application filed March 16, 1928, Serial No. 262,307, and in Great Britain March 1, 1927.

This invention relates to the manufacture of fencing, railings, or gates hereinafter referred to as fencing, and the invention has for its object to provide a simple, strong and durable form of metal fencing which will be comparatively inexpensive to construct.

Referring to the drawings:—

Figure 1 is an elevation showing one section of one form of fencing constructed according to this invention.

Figure 2 is a perspective view of one of the strips forming part of the grid of the fencing shown in Figure 1.

Figure 3 is a part sectional view of part of two strips showing a method of fixing them together.

Figures 2 and 3 are both drawn to larger scales than Figure 1.

Referring to the drawings 1 and 2 are vertical pillars which may be solid or hollow as desired, and which may be in one piece or built up of a series of sections. Each pillar is preferably provided with a foot or flange 3 and with supports 4 which may be in the form of strip metal secured at one end to the pillars 1 and 2. It will be understood that in a fencing of considerable length, the fence will be made up of a number of sections that there will consequently be a greater or smaller number of vertical posts 1 and 2 according to the length of the fence, but Figure 1 shows two of such posts and a grid arranged between them, and it will be appreciated of course, that similar grids are arranged between all pairs of posts or uprights.

The posts 1 and 2 are pressed together by means of horizontal bars, strips or rods 5 and 6 secured at one end to the post 1 and at the other end to the post 2 by means of brackets 7, or in any other suitable manner. The member 5 may, if desired, be provided with a series of upright spikes or the like 8 disposed at intervals apart.

The posts 1 and 2 and the cross-members 5 and 6 form a frame, and the frame is filled wholly or partially by means of a grid which is constructed of a number of lengths of strip metal 9, each of which is pressed into a zigzag, undulating or sinuous form, these strips being arranged side by side and each two adjacent strips being assembled in reverse relationship and secured together by means of rivets 10 passing through holes 11 in the strips, or in any other suitable and

convenient manner, such as, for instance, by welding, brazing or the like. The form of strip shown in the drawings consists of a number of inclined portions 12, having vertical portions or facings 13 disposed between them, and having horizontal ends 14 and 15, which ends are employed for securing the strips to the horizontal members 5 and 6 by means of rivets or the like. The said ends 14, 15 of the respective strips extend in opposite directions and meet between each adjacent pair of strips so that they almost continuously cover the horizontal members 5, 6 and effectually brace the grids or strips 70 and greatly increase the strength of the structure as a whole. If desired the end strips of each grid may be provided with a vertical portion 16, Figure 1, at the end of the portion 14, and these portions 16 may be secured to the uprights 1 and 2.

As can be clearly seen from Figure 1 and Figure 3, the vertical portions 13 of adjacent strips 9 are placed one along the other and in contact with each other, and they are secured in this position by means of the rivets 10 or in any other convenient manner as described above.

When a strip 9 is the end one in a grid, then it will be understood that some of the portions 13 instead of abutting the adjacent strip, contact with a post or upright, and are secured thereto by set screws or in any other desirable manner.

If desired the vertical portions 13 may be each provided with a semi-circular or other non-planar part 17.

The strips 9 are arranged in the frames formed by the uprights 1 and 2 and the horizontal members 5 and 6 in such a manner 95 that the width of the strips is transverse to the plane of the fence.

It will be appreciated that although a sinuous form of strip 9 has been shown in the drawings, these strips can easily be stamped to any suitable and desired zig-zag undulating, or sinuous shape and thus various ornamentalations may be produced quite readily and cheaply.

In constructing fencing or the like, the strips 9 need not necessarily be placed vertically as shown in the drawings, but may be placed horizontally, vertical, or obliquely as required, and additionally plain, flat or other strips may be used in between each two or 110 any two of the zigzag or sinuous strips if necessary.

Strips constructed according to the present invention have the advantage that they are easily shaped and consequently if the width of a frame is not the exact multiple 5 of the width of the strips comprising the grid to go into the said frame, then these strips can easily be closed in a little or expanded according to requirements so that they fit exactly into the frame. Such expansion or contraction is greatly facilitated by 10 the provision of the non-planar portions 17.

This invention has been shown in the drawings and herein described with reference to fixed fencing, but it will readily be understood that it might, if desired, be applied to 15 gates or other like structures.

What I claim then is:—

1. Openwork structures having a number 20 of frames comprising vertical and horizontal members, and grids adapted to be placed in said frames, each grid comprising lengths of strip metal pressed into sinuous form, each strip of metal being provided with a plane portion adapted to lie along a corresponding 25 portion of an adjacent strip or along a side of a vertical member of a frame when the strip of metal is an end one in a grid each two adjacent strips of metal being assembled in reverse relationship and said plane 30 portions being secured together, said grids being adapted to be placed in one of the said frames with the width of the strips disposed

transversely to the plane of the structure, and said strips having oppositely extending attachment parts at their ends adapted to 35 be secured to the said frame members with said attachment parts of each strip in contact with those of the next adjacent strip.

2. Openwork structures having a number of frames comprising vertical pillars and 40 horizontal members extending between said pillars, and grids adapted to be placed in said frames, each grid comprising lengths of strip metal pressed into sinuous form, each two adjacent strips of metal being assembled in reverse relationship, each strip of metal being provided with plane portions adapted to lie along corresponding portions of an adjacent strip or along a side of a vertical member of a frame when the strip of 45 metal is an end one in a grid when the strips are assembled and non-planar parts intermediate the ends of said plane portions, the said strips being secured together where said plane portions contact and with said non-planar parts out of mutual contact, and each grid being adapted to be placed in one of the said frames with the width of the strips disposed transversely to the plane of the structure, and said strips having attachment parts adapted to be secured to the said 50 frame members.

In witness whereof I affix my signature.
JOHN WILLIAM EDWARD BETTLES.
